UNITED STATES PATENT OFFICE.

CHARLES E. HOWE, OF ROCHESTER, NEW YORK, ASSIGNOR TO UNITED SHOE MACHINERY COMPANY, OF PATERSON, NEW JERSEY, A CORPORATION OF NEW JERSEY.

CUTTING-MACHINE.

1,070,133.

Specification of Letters Patent. Patented Aug. 12, 1913.

Application filed April 3, 1912. Serial No. 688,240.

To all whom it may concern:

Be it known that I, CHARLES E. HOWE, a citizen of the United States, residing at Rochester, in the county of Monroe and 5 State of New York, have invented certain Improvements in Cutting-Machines, of which the following description, in connection with the accompanying drawings, is a specification, like reference characters on 10 the drawings indicating like parts in the several figures.

This invention relates to cutting machines and particularly to means for maintaining the material to be cut in such machines in 15 proper position for the cutting operation or operations.

The invention is herein shown as applied to a clicking machine, the illustrated embodiment of the invention being especially 20 adapted for preventing the cloth or other material from which blanks are to be cut from being drawn over the edge of the cutting bed of a machine of this type. It will be understood, however, that the invention 25 is not restricted to use with clicking machines.

In cutting cloth for linings or in cutting any other material which is of substantially uniform texture throughout it is customary 30 to superpose several layers of material so that a number of blanks may be cut at each operation. When a number of layers of material are thus superposed, it is important that there be no relative slipping of the 35 layers, particularly after one or more cuts have been made through the layers. Moreover the cloth or other material is usually of a length considerably greater than any of the dimensions of the cutting bed of the machine in which it is to be cut, and it is therefore important to prevent the weight of the material which projects beyond the edge of the bed from pulling the material which is on the bed over the edge. One of the 40 most common practices is to stick awls through the material into the cutting block. If the material is comparatively wide a number of awls are required and it takes considerable time to so place them that they 45 will hold the material properly and also to remove them when the material is to be moved.

One object of the invention, therefore, is to provide convenient holding or clamping 55 means which will hold the material against

movement over the bed or block during the operations upon the part of the material which is on the bed or block and will also effectually prevent relative movement to each other of the different layers. 60

Another object of the invention is to provide holding or clamping means which will be so located with respect to the cutting bed or block that it will not interfere with the cutting operation upon any part of the bed 65 or block.

Other objects of the invention are to provide means for effecting easily the clamping and unclamping operations, to provide means for protecting the finished surface of 70 the material from injury by contact with the block or other parts of the machine, to provide means for receiving the scraps which will be located in convenient relation to the cutting and clamping means, and in 75 general to provide a construction which can be manufactured cheaply and which can be applied readily to any of the well-known types of cutting machines.

In the accompanying drawings,—Figure 80 1 is a perspective view of a clicking machine to which the present invention has been applied; and Fig. 2 is a detail section illustrating the manner in which the material to be cut and the protective material are 85 passed between the clamp members.

The clicking machine herein shown is of well-known construction, being extensively used in the manufacture of boots and shoes. 90 In this machine a cutting block 2 is supported upon a table 4 carried by a bracket attached to the frame 6. The material to be cut is spread out on the block 2. A die having the outline of the blank to be cut is then placed upon the material and the presser member 8, constituted by a swinging arm attached to a post 10, is swung into position over the die after which the operator depresses the handle 12 which he has grasped to swing the presser member into 95 position, thereby actuating a clutch through which the fly wheel 14 is connected to the driving shaft and through suitable connections reciprocates the post 10 to cause the presser member to perform the cutting operation. 100

The various details of construction of this machine are more fully shown and described in United States Letters Patent No. 921,503, to Arthur Bates, dated May 11, 1909; No. 110

1,004,757 to H. H. Eaton, dated Oct. 3, 1911; and No. 1,011,903 to Arthur Bates, dated Dec. 19, 1911.

- 5 The principal use made of this machine is in cutting upper leather for boots and shoes. It is, however, used to a considerable extent for cutting other material, such as linings for boots and shoes, and when the material which is to be cut is of substantially uniform texture throughout it is customary to superpose several layers of material and thus cut several blanks at one operation. This is the usual practice when cutting linings.
- 10 15 To prevent relative slipping of the different layers of material when the machine is used in this manner, thereby preventing the holes formed in the successive layers by a blank cutting operation from moving out of register, whereby material would be wasted, and also to prevent the weight of the material which hangs over the edge of the cutting block from causing that on the block to move over the edge, the illustrated clamping means has been provided. This means comprises upper and lower clamp members 16 and 18 respectively, which may conveniently consist of cylindrical tubing, the upper clamp member in the illustrated construction being stationary and being attached at its ends to lateral supports 20 and 22 which may conveniently consist of tubing of the same diameter as the tubing used for the clamp members 16 and 18, the member 16 being attached to the supports 20 and 22, preferably by sleeves 24 and 26 which are rigidly confined upon the supports 20 and 22 and serve as stops for other sleeves 28 and 30 slidably mounted upon the supports 20 and 22 and carrying the movable clamp member 18. The movable clamp member 18 is normally yieldingly pressed into clamping relation to the stationary clamp member 16 by springs 32 and 34 surrounding the respective supports 20 and 22 and bearing respectively at their upper ends against the sleeves 28 and 30 and at their lower ends against other sleeves 36 and 38 rigidly confined upon the supports 20 and 22.
- 15 20 25 30 35 40 45 50 55 60 65 70 75 80 85 90 95 100 105 110 115 120 125 130
- 50 In order to separate the clamp members 16 and 18 to permit the material to be inserted between them or to be drawn through the clamp, means is provided for depressing the movable member 18 against the tension of the springs 32 and 34. The illustrated means comprises a cross-bar 40, attached at its ends by links 42 and 44 to ears upon the sliding sleeves 28 and 30, and a treadle 46 pivoted in a stand 48 which may be attached to the floor and connected by a chain 50, or any other suitable means, to the cross-bar 40. The chain 50 is illustrated since it forms a connection which can conveniently be adjusted to different heights of cutting blocks.
- 55 60 65 70 75 80 85 90 95 100 105 110 115 120 125 130
- 65 The lateral supports 20 and 22 preferably

enter sockets 52 and 54 in stands which may be attached to the floor, the supports being slideable in the sockets whereby the clamp may be adjusted to adapt it to varying heights of cutting blocks. The supports are secured in their different positions of vertical adjustments by split sleeves 56 and 58 clamped upon the supports and resting upon the upper ends of the sockets 52 and 54.

When cutting cloth or other material having a finely finished surface, such as plush, it is desirable to protect this surface from the cutting block. The usual practice is to insert a piece of paper under the cloth. In order to provide convenient means for holding the paper or other protective material a rod 60 adapted to receive a roll of paper has been provided with supports 62 and 64 which may be clamped to a cross-bar 66 connecting the sleeves 36 and 38. The rod 60 may be clamped to the bar 66 in different positions of adjustment about said bar whereby the position of the rod 60 may be adapted to the size of the roll of paper, to the position of the clamp with respect to the cutting block, and to the position of the container 68 or other means for holding the cloth or other material to be cut. In Fig. 2 is shown the manner of using the clamp, the cloth being passed in front of the movable clamp member 18 and then between the clamp members, and the paper being passed between the members in such manner that it comes beneath the cloth upon the cutting block.

To provide convenient means for receiving the scraps which are left from the cutting operation, a bag holder 70 is arranged at one side of the bed, the illustrated bag holder comprising a rod bent into substantially semicircular form and having an eye which receives one of the clamping bolts 72 of the cutting block, the rod being provided with pins 74 over which the bag 76 may be hooked.

It will be noted that the clamp herein shown is located so that the portion of the material which is engaged by it lies in a plane below the plane of the material which is upon the bed. This is the preferable arrangement of the clamp since, although it is obvious that the material clamped might lie in the same plane as the material upon the surface of the bed without any disadvantage other than having the clamp project above the surface of the bed, it would be quite objectionable to have the material clamped in a plane above that upon the bed since it would tend to lift the material on the bed slightly, and any pressure upon the material between the clamp and the edge of the bed would tend to move the material over the surface of the bed. To avoid any possibility of clamping the material so that the portion clamped will lie in a plane above the plane

of that on the bed and also to have the clamp so located that it will not interfere with any operations upon the bed, it is preferable to locate it as shown so that it will 5 clamp the material in a plane below the surface of the bed or below the plane in which the material upon the bed lies and will itself not project above the surface of the bed.

10 Having described my invention, what I claim as new and desire to secure by Letters Patent of the United States is:—

1. In a machine of the class described, the combination with a bed for supporting material to be cut and a presser member movable into engagement with a die supported upon said material, of means for clamping during the cutting operation a portion of said material that projects beyond the edge 20 of the bed.

2. In a machine of the class described, the combination with a bed for supporting material to be cut and a presser member movable toward the bed and adapted to engage 25 a movable die upon the bed, of means for clamping during the cutting operation a portion of said material that projects beyond the edge of the bed, said means being constructed to operate outside the edge of 30 the bed and having provision for vertical adjustment to adapt it to beds of different heights.

3. In combination, a cutting bed, a presser member adapted to coöperate with substantially all portions of the bed to effect the cutting operation, and means outside the bed for clamping the material to be cut which projects beyond the edge of the bed comprising clamping members extending entirely 40 across the width of the material.

4. In combination, a cutting bed, a presser member adapted to coöperate with substantially all portions of the bed to effect the cutting operation, and means outside the bed 45 for clamping the material to be cut which projects beyond the edge of the bed, and treadle operated means for controlling said clamping means.

5. In combination, a cutting bed, a co- 50 operating presser member movable to engage a die wherever located on said bed, means outside the bed for clamping the material to be cut which projects beyond the edge of the bed comprising an upper stationary clamping member and a lower movable clamping member yieldingly maintained normally in clamping relation to said upper clamping member, and manually controlled means for separating said members.

60 6. The combination with a cutting bed and means outside the bed for clamping the material to be cut which projects beyond the edge of the bed, of means for supporting a

roll of paper or other protective material in position to pass through the clamping means 65 below the material to be cut.

7. In a machine of the class described, the combination with a bed and a coöperating presser member adapted to engage a movable die wherever located on said bed, of 70 means outside said bed for clamping the material to be cut which projects beyond the edge of the bed, said means extending the entire length of said bed.

8. In combination, a cutting bed, a presser member movable into coöperative relation to substantially all portions of the bed, and means outside the bed for clamping the material to be cut which projects beyond the edge of the bed, said means comprising 80 lateral supports, a stationary clamp member connecting said supports, a movable clamp member guided at its ends upon said supports, and a spring upon each support operating to press said movable clamp member toward stationary clamp member.

9. The combination with a cutting bed and means for clamping the material to be cut which projects beyond the edge of the bed, of adjustable means for supporting a 90 roll of paper or other protective material in position to pass through the clamping means below the material to be cut.

10. In combination a cutting bed and means outside the bed for clamping the material to be cut which projects beyond the edge of the bed, said means comprising vertically adjustable lateral supports, a stationary clamp member connecting said supports, a movable clamp member guided at 100 its ends upon said supports, means acting normally to hold said movable member yieldingly in clamping relation to said stationary member, and means for separating said members comprising a cross-bar linked 105 at its ends to the ends of said stationary member and a treadle connected to said cross-bar between its ends.

11. In combination, a cutting bed, a presser member movable into engagement 110 with a die wherever located on the bed, and means outside the bed for clamping during the cutting operation the material to be cut which projects beyond the edge of the bed, said means being so located with respect to 115 the surface of the bed that the portion of the material clamped will lie in a plane below the plane of the material upon the bed.

In testimony whereof I have signed my name to this specification in the presence of 120 two subscribing witnesses.
